PROCESS FOR MANUFACTURING SUGAR

Roy L. Lay, Rocky Ford, Colo., assignor of one-third to Walter J. Kellogg and one-third to I. W. Reed, both of Rocky Ford, Colo.

Application June 27, 1938, Serial No. 216,076

2 Claims. (Cl. 127—50)

This invention relates to an improvement in processes for the manufacture of sugar, more particularly beet sugar.

The principal object of the invention is to provide a process step which will reduce the lime content of the juices before evaporation so as to reduce the formation of scale deposits on the heating surfaces of the factory evaporators and vacuum pans.

10 Another object of the invention is to provide a simple process step which can be easily accomplished in the standard beet sugar factory without changes or additions to the equipment thereof, and without requiring additional re-

15 agents or treatments, which will substantially eliminate lime salts and other soluble impurities from the thin juice to produce a higher purity of juice and a higher sugar yield therefrom.

Other advantages will become apparent from 20 the following description of the process and from its use.

In the following description of the process, reference is had to the accompanying drawing which illustrates a typical flow diagram of the 25 first carbonation step in the usual sugar manufacturing process with this invention incorporated therein.

Usual process

30 In the usual process for the extraction of beet sugar, the juices are extracted by diffusion from the beet pulp by the repeated passage of hot water or hot juices therethrough in the cells of a diffusion battery. The raw juice from the diffusion battery, indicated by the flow line 10 on the diagram, is stored in a raw juice tank 11.

35 The juice is drawn from the storage tank 11, heated in raw juice heaters, indicated at 13, and passed to first carbonation tanks, 14, where it is treated with CO₂ gas to precipitate the lime and suspended solid matter therefrom. It is then reheated if necessary in a first carbonation heater, 15, and passed to thickeners or settling tanks 16 to settle out the solid suspensions.

40 The partially clarified juice from the thickeners 16 is passed to a suitable receiving tank 17 and, from thence, to second carbonation heaters 18. The latter raise the temperature of the juice to the proper point for a second carbonation which is carried out in second carbonation tanks 19 to precipitate the remaining lime. From

45 the second carbonation tanks, the carbonated juice is passed as indicated by the flow line 30 passed to filter presses designated "second carbonation presses" to filter out of the final solids

thrown down in the second carbonation. From thence the clarified juice passes to the evaporators and pans for crystallizing out the sugar.

The sludge and thickened juice from the thickeners 16 passes to a sludge mixing tank 21, thence to first carbonation filter presses 20 usually of the "Oliver" vacuum type. The presses filter the sludge or "mud" from the thickened juice, producing a "pick-up" in receiver 25. The pick-up juice is substantially clear but carries a high 10 percentage of excess lime from the first carbonation. The mud or sludge cake from the presses is washed before being discarded to waste, as indicated at 28. The wash waters, carrying the remaining sugar and more or less solid matter, are passed to a wash receiver 26.

In the usual factory, the approximately one-third of the pick-up juice is passed by means of a pump 34 from the receiver 25 to a low melter, 27, where the temperature is raised to 20 lessen the viscosity of the juice and it is then pumped back by means of a pump 35 to the raw juice line as indicated by the flow line 24. The remaining two-thirds was formerly pumped back to the flow line 30, as indicated by the broken 25 flow line 33—32, and is then passed directly to the 2nd carbonation presses without additional carbonation.

In the present factories one-half of the sweet wash waters are diverted from a sweet water 30 pump 36 and used for thinning saccharate cake, in a saccharate mixing and heating tank 29, and are then passed, with the dissolved saccharate cake by means of a saccharate pump 37 to the raw juice line, as indicated by the line 38. The 35 remaining half of the sweetwaters are at present passed directly from the pump 36, back to the second carbonation line 30, as indicated at 33, without further carbonation.

Both the returned pick-up juices and the returned wash waters carry lime and other soluble and insoluble impurities, a large percentage of which could be eliminated by an additional carbonation. Yet these sweetwaters and juices are passed directly to the second carbonation presses 45 without carbonation and thence to the evaporators and pans where the impurities are eliminated in the formation of heavy scale deposits upon the heating surfaces.

Improved process

In this improved process the old flow lines 32 and 33 are eliminated and the excess pick-up juice from the pick-up receiver 25, and the excess sweetwater from the wash receiver 26 is 55

passed back to the raw juice flow line ahead of the first carbonation tanks 14, as indicated by the flow line 31. From thence it flows with the incoming raw juice to the first carbonation tanks 5 where it is retreated with the caustic lime and CO₂ and passed to the thickeners 16, and from thence to the second carbonation and filter phases.

By this method all the sweetwaters and all 10 pick-up juices are subjected to repeated carbonation until they reach a stage of purity equal to that of the juice entering the second carbonation. Thus, the second carbonation, not only eliminates the lime and other soluble impurities 15 from the raw juice but also, at the same time, eliminates them from the intermixed sweetwaters and pick-up juices without additional equipment. No additional pumps are required since the present pumps 34 and 36 are employed 20 in the return of the juice to the first carbonation.

The elimination of the lime and other soluble impurities from the evaporators and pans results in a great saving in fuel and equipment due to the elimination of objectionable scale as 25 well as the saving of time and materials ordinarily required for the periodical removal of the scale deposits.

The process is not necessarily limited to the exact procedure and process as shown on the 30 diagram and as described herein. It is only to be considered as limited by the terms of the

accompanying claims in which it is intended to claim all novelty inherent in the invention as broadly as permissible in view of the prior art.

Having thus described the invention, what is claimed and desired secured by Letters Patent 5 is:

1. In a process for the manufacture of sugar of the type having the following steps, carbonation of the juice, filtration of the juice from the sludge, pressing of the sludge to extract the 10 juice remaining therein, washing of the pressed sludge cake, a second carbonation of the juice from the filtration step, a pressing of the juice from the second carbonation step; the intermediate step of returning all of the waters from 15 the washing step and all of the juice from the first pressing step to the first carbonation; thence passing them through the second carbonation to further purify them before passing them to the second pressing step along with juices from 20 the second carbonation.

2. The herein described method of reducing the lime content of the juices before evaporation in a sugar manufacturing process in which the incoming crude juice is successively subjected 25 to a first and a second carbonation step before evaporation, comprising: introducing into the incoming crude juice before carbonation the wash waters and pick up juices from the first carbonation step.
